ATTORNEY

UNITED STATES PATENT OFFICE.

JOSEPH BLOCK, OF NEW YORK, N. Y.

PORTABLE ELECTRIC LIGHT.

971,241.

Specification of Letters Patent. Patented Sept. 27, 1910.

Application filed February 21, 1910. Serial No. 545,209.

To all whom it may concern:

Be it known that I, JOSEPH BLOCK, a citizen of the United States, residing in the city, county, and State of New York, have 5 invented a certain new and useful Improvement in Portable Electric Lights, of which the following is a specification.

The present invention has particular relation to the arrangement or construction 10 whereby the circuit of a portable electric lamp is closed or opened at will.

The principal object of the invention is the provision of means of an inexpensive, simple and reliable character and capable 15 of convenient application to any form of portable electric lamp whereby the lamp may be lighted or extinguished.

The invention is shown in the preferred form in the accompanying drawings where- 20 in—

Figure 1 is a side elevation of a portable lamp showing the circuit closer in plan, Fig. 2 is a longitudinal section of the lamp, showing the circuit closer partly in eleva- 25 tion and Fig. 3 is a longitudinal section of one portion of the circuit closer.

The usual casing of the lamp is shown at 10, the same being made of insulating material and provided with a threaded metal end 11 which is applied to the exterior of the casing 10 at the rear end thereof. The usual batteries are shown at 12, 13 and are held in place by the cap 14 which screws onto the threaded end 11, and, preferably, 15 by the spring 15. The usual lamp 16 screws into the reflector 17 behind the lens 18 in a well known manner; the whole being secured by a threaded thimble 19 which screws onto the upper end of the lamp. As usual 20 in these devices, one terminal of the lamp 16 makes contact at 20 with one terminal of the battery while the other terminal of the lamp is electrically connected to the metal reflector 17.

45 The circuit closing means comprises two portions, one of which is composed of a fixed metal plate 21 riveted to the exterior of the casing and kept in permanent electric connection with one terminal of the lamp by means of the conductor 22 and the reflector 17. The usual insulating material 50 23 surrounds the battery cells and prevents their making contact with the conductor 22 or other metal parts projecting into the cas- 55 ing 10. The other portion of the circuit closer comprises a sliding spring tongue 24

within an appropriate metal box 25 provided with a slot 26 through which projects the pin 27 fastened to one end of the spring 24 by means of a thread and a nut 28 and having at its top a button 29 which can be pushed by a thumb or finger of the user to slide the tongue 24 back and forth. I prefer to fix the nut 28 to the spring 24 by means of solder 30 to prevent accidental 60 loosening of the button.

The box 25 is fastened to the exterior of the casing 10 preferably by rivets as shown, and said box, together with the spring 24, is maintained in permanent electric connection, by means of the conductor 31, with the thread end 11, and therefore through the cap 14 and spring 15, with the zinc terminal of the battery. As shown in Fig. 2, when the spring 24 is thrust forward into 70 dotted line position, circuit is closed through the lamp by contact of the spring with the upwardly bending metal plate 21. Retraction of the spring to the position shown in Fig. 1 will break the circuit and put out the 75 lamp.

In order to facilitate proper construction of the box which contains the spring 24, I prefer to make the same in two parts comprising a relatively wide plate 32 which is 80 riveted directly to the casing and an upper slotted section, to which the numeral 25 is applied, which is open at the bottom and has tangs or extensions 33 which pass through appropriate openings in the lower plate 32 and are then turned over to secure the two sections of the box together. By use of this construction the firm fastening of the spring 24 under sufficient flexure to provide a strong spring pressure against 90 the box 25 can be accomplished before the two sections of the box are fastened together. The two sections can then be assembled and secured together, after which the whole can be riveted to the casing as 95 shown.

What I claim is—

1. In a portable electric lamp comprising an exterior casing, a battery within the same and an incandescent lamp bulb; in combination with a two part circuit closer, comprising a fixed plate having an upwardly bulged portion fixed to the exterior of the said casing, a two part box also fixed to the exterior of the said casing and provided with a slot, 105 a spring tongue sliding within the said box and adapted to be brought into contact with

said bulged plate, a button for imparting motion to said tongue and a pin extending over said button through the slot in the said box and fixed to said spring, substantially as described.

2. In a portable electric lamp, a circuit closer comprising a fixed plate; in combination with a two part box comprising a second fixed plate and an upper slotted section having tangs for securing the same to said second named plate, a slotted spring

tongue within said two part box, a threaded pin passing through the slot in the upper section of said box secured to the said spring tongue and a button above the slot in said box fixed to said pin, substantially as described. 15

JOSEPH BLOCK.
